ATTORNEY

UNITED STATES PATENT OFFICE.

CHARLES A. MAHER, OF WALLOWA, OREGON.

COMBINATION SOAP AND APPLICATOR HOLDER.

1,275,456.

Specification of Letters Patent. Patented Aug. 13, 1918.

Application filed November 24, 1917. Serial No. 203,869.

To all whom it may concern:

Be it known that I, CHARLES A. MAHER, a citizen of the United States, residing at Wallowa, in the county of Wallowa and

5 State of Oregon, have invented a new and useful Combination Soap and Applicator Holder, of which the following is a specification.

The invention relates to a container, and 10 more particularly to the class of combination soap and applicator holders.

The primary object of the invention is the provision of a holder of this character, wherein a soap stick and applicator therefor 15 will be inclosed when not in use, thus protecting the same and yet making them readily and easily accessible for use, the applicator being in the form of a rubber sponge fastened in position for the convenient handling thereof to enable the lathering of the face of the user, the soap also being held for 20 its free application to the face for shaving purposes.

Another object of the invention is the provision of a holder of this character which is extremely simple and durable in construction, enabling the soap and applicator to be conveniently held in a compact manner, and also which is inexpensive to manufacture.

25 With these and other objects in view, the invention consists in the features of construction, combination and arrangement of parts as will be hereinafter fully described, illustrated in the drawing and pointed out in 30 the claims hereunto appended.

In the accompanying drawing:

Figure 1 is a vertical longitudinal sectional view through the holder constructed 40 in accordance with the invention, showing the soap stick and applicator held therein;

Fig. 2 is a fragmentary side elevation partly in section, showing the applicator removed from the holder and fastened thereon for use;

45 Fig. 3 is a perspective view of the soap support;

Fig. 4 is a perspective view of the applicator.

Similar reference characters indicate corresponding parts throughout the several views in the drawing.

Referring to the drawing in detail, the holder comprises an inverted substantially cup-shaped support forming a connector 10, 50 preferably made from metal, having formed exteriorly thereof on its side wall 11 screw

threads 12 and 13 respectively, which are separated from each other through the medium of an intermediate external bead 14 extending circumferentially of the side wall 60 11 of said connector 10, the threads 12 and 13 being located on opposite sides of the bead 14 and extend to opposite ends of the connector 10 as clearly shown in Figs. 1 and 3 of the drawing for a purpose presently 65 described.

Passed through a suitable hole centrally located in the connector 10 is a fastener 15 such as a screw for securing a soap stick 16 within the connector, the soap stick being of the usual well known construction, and is adapted for use in shaving. The connector 10 forms a socket for the inner end of the soap stick 16, which, in cross section, is preferably the size of the socket in the 75 connector to be received therein.

70 Detachably engaged on opposite ends of the connector 10 are removable caps 17 and 18 respectively, each being open at one end and closed at its opposite end, the open end 80 being internally threaded for the detachable engagement of both of the caps on the connector as is clearly shown in Fig. 1 of the drawing. The cap 16 is of a length and size to inclose the soap stick 16, while the cap 85 18 forms a chamber 19 for receiving an applicator hereinafter fully described.

The applicator comprises a rubber sponge body 20 having a relatively hard rubber base 21 which is of greater diameter than the 90 diameter of the body 20 to constitute a marginal flange 22 circumferentially of the sponge body for a purpose to be presently described.

The closed end of the cap 18 is formed 95 with external screw threads 23 for the detachable engagement of an internally threaded clamping collar 24 therewith which is formed with a central opening 25 for accommodating the sponge body 20 of the applicator, 100 which is passed through the central opening 25 to have the base 21 rest upon the closed end of the cap 18, with the marginal flange 22 engaged by the collar 24 when screwed upon the closed end of the cap 18 so that 105 the applicator is made fast thereon for the use of the same, after the application of soap, to the face of the user for lathering purposes in shaving.

The cap 18 houses the applicator when 110 not in use, and in this instance is detachably engaged on the connector 10 for inclosing

the applicator within the chamber 19. It is necessary to remove the cap 18 from the connector 10 to extract or take out said applicator for use, which applicator is then applied to the closed end of the cap 18, the collar 24 being removed therefrom and subsequently applied thereto for the fastening of the applicator upon the cap as is clearly shown in Fig. 2 of the drawing.

10 The cap 17 is detached from the connector 10 for exposing the soap stick 16 for use. The caps 17 and 18, each is preferably made from metal and likewise the collar 24 is made from metal.

15 When the soap stick and applicator are inclosed in the holder, the same will be protected and can be conveniently carried from place to place so that the holder is handy for travelers. Both the soap and applicator are readily accessible on removal of the caps, and will be held in a convenient manner for easy use.

20 It is to be understood that changes, variations and modifications may be made in the invention such as come properly within the scope of the appended claims without departing from the spirit of said invention or sacrificing any of its advantages.

25 From the foregoing, it is thought that the construction and manner of use of the holder, soap stick and applicator will be clearly understood, therefore a more extended explanation has been omitted.

30 What is claimed is:

35 1. The combination with a connector forming a support for a soap stick, of caps removably fitted on the connector at opposite ends thereof, one of the caps being designed to house an applicator, and the other 40 the soap stick, and a clamping collar carried by one of the caps for detachably fastening said applicator thereto on its removal from the cap.

45 2. A holder of the character described comprising a connector of substantially cup-shape having external screw threads at its opposite ends, caps detachably engaged with the threaded ends of the connector, means for fastening a soap stick in the connector 50 and inclosed by one of the caps, an applicator removably held in one of the caps, and a clamping collar engaged exteriorly on one of the caps for fastening the applicator thereon for use.

55 3. A holder of the character described comprising a connector of substantially cup-shape having external screw threads at its opposite ends, caps detachably engaged with the threaded ends of the connector, means for 60 fastening a soap stick in the connector and inclosed by one of the caps, an applicator removably held in one of the caps, a clamp-

ing collar engaged exteriorly on one of the caps for fastening the applicator thereon for use, and a marginal flange on the applicator 65 and engaged by the clamping collar to detachably fasten said applicator to the cap.

4. A holder of the character described comprising a connector of substantially cup-shape having external screw threads at its 70 opposite ends, caps detachably engaged with the threaded ends of the connector, means for fastening a soap stick in the connector and inclosed by one of the caps, an applicator removably held in one of the caps, a 75 clamping collar engaged exteriorly on one of the caps for fastening the applicator thereon for use, and a marginal flange on the applicator and engaged by the clamping collar to detachably fasten said applicator to the cap, the collar being formed with an 80 opening to permit the encircling thereof about the applicator when fastening it to the cap.

5. A holder of the character described 85 comprising a connector of substantially cup-shape having external screw threads at its opposite ends, caps detachably engaged with the threaded ends of the connector, 90 means for fastening a soap stick in the connector and inclosed by one of the caps, an applicator removably held in one of the caps, a clamping collar engaged exteriorly on one of the caps for fastening the applicator thereon for use, and a marginal flange 95 on the applicator and engaged by the clamping collar to detachably fasten said applicator to the cap, the collar being formed with an opening to permit the encircling thereof about the applicator when fastening it to the cap, the applicator being formed with a rubber sponge body and a relatively hard sponge base.

6. In combination with an inclosure for 105 an applicator to wholly inclose the same when not in use, said inclosure being threaded at one end, a clamping collar having an opening through which the body of the applicator is passed leaving a flanged portion 110 of the applicator contained within the collar, the latter being threaded to engage with threads on the inclosure, whereby upon removing the applicator from the inclosure it may be passed through the opening of 115 the clamping collar and clamped on the end of the inclosure in position for use.

In testimony that I claim the foregoing as my own I have hereto affixed my signature in the presence of two witnesses.

CHARLES A. MAHER.
